UNITED STATES PATENT OFFICE.

ARTHUR WADE AND HARRY L. VAN ZILE, OF NEW YORK, N. Y., ASSIGNEES TO VAN ZILE VENTILATING CORPORATION, OF NEW YORK, N. Y., A CORPORATION OF NEW YORK.

VENTILATING DEVICE.

Application filed September 30, 1922. Serial No. 591,549.

This invention relates generally to means for providing a continuous or at least fairly constant flow of fresh air into closed apartments, and it pertains more especially to a device of this kind adapted for insertion into a door in order to afford ventilation therethrough.

One object of the invention is to produce an improved device of the nature set forth which may be composed entirely of sheet-metal, and shall include interspaced members that are individually apertured and carry oppositely directed vanes, the latter being formed integral with the respective members and so arranged as to permit free circulation of the air, while obstructing vision and preventing the passage of light.

Another object is to provide a device of the character described, wherein the spaced apart members and their respective vanes are associated in a unitary structure, with side pieces attached thereto by means of elements formed from the edges of the members themselves.

A further object is the production of a device of the type specified having a closure capable of controlling the flow of air transversely of the said structure through its apertured members, and fitted to slide in guides formed with opposite edges of one of the latter.

Still another object is the provision in a device of the class mentioned of means for noiselessly cushioning the impact of the said closure against the terminals of the slideway within the said guides, at the completion of its travel therein, either to close or open the apertures in the said members.

A still further object is to furnish a practical device of the sort indicated, consisting of few, simple parts, of light but strong, rigid and durable construction; convenient to manipulate; reliable in operation; and easily maintained in working order, as well as readily fitted to both new and existing doors; besides being amenable to low cost of manufacture.

Other objects and advantages of the invention will become apparent as the specification proceeds.

With the aforesaid objects in view, the invention consists of the novel combinations and arrangements of parts hereinafter described in their preferred embodiments,

pointed out in the subjoined claims, and illustrated on the annexed drawing, wherein like parts are designated by the same reference characters throughout the several views.

Briefly described, the invention under consideration comprises in its organization a pair of plates disposed in parallelism a short distance apart one from the other. These plates are slotted each at alternate intervals, so as to form therein facial apertures arranged in staggered relation. The material displaced by the slitting is bent inwardly into the space occurring between the plates and constitutes vanes that are disposed angularly with respect to the two series of apertures. The free, inner extremities of these vanes are offset beyond one another so as to block the vision and the passage of light from either side of the combined plates, irrespective of the apertures therein, no matter at what angle they may be viewed. Still this is accomplished without interfering with the circulation of air through and across the apertured plates. Interposed between the inside faces of the latter, and associated with the transverse ends of the vanes, are channel-shaped members that govern the spacing of the plates relatively to each other. The edges of one of the plates are carried outwardly past the flanges of the said channel-shaped members and then bent back inwardly in such a manner as to encompass the same, one plate being thereby clamped upon the flanges of the adjoining member. Guides are also formed with the edges of the other plate for a slide having a number of openings adapted to be brought opposite the apertures in the latter and thus controlling the flow of air therethrough. This plate is maintained rigidly in position on the adjacent flanges of the channel-shaped members, as well as the said guides, by means of keepers, preferably struck up from it near the edges thereof and thence bent over the last-named flanges. The opposite edges of the slide are thickened, as by folding the same upon themselves, in order to hold the body thereof at the required distance from the contiguous face of the plate. Besides, the curved extremities of the folded edges are considerably less than the inside radii of the guides and afford complete freedom of

motion to the slide. The guides are stopped up as well as reinforced at their terminals, by retainers holding resilient buffers in place that serve to cushion the impact resulting from the slide's movement thereagainst, when reaching the limit of its travel at either end. This naturally contributes to noiseless operation. The outer faces of the slide and of the plate remote therefrom are correspondingly reinforced, intermediately of their respective openings and apertures, by hollow ribs formed in opposed relation to one another, which permit the use of comparatively light material, without the sacrifice of either strength or rigidity, in the manufacture of the device. A knob, affixed in plain view to the outer face of the slide, provides a convenient and unobtrusive grip for the manipulation thereof in opening or closing the ventilating apertures.

The advantages of the invention as here outlined are best realized when all of its features and instrumentalities are combined in the one and same structure, but, useful devices may be produced embodying less than the whole.

It will be obvious to those skilled in the art to which the invention appertains, upon becoming conversant with the details thereof, that the same may be incorporated in several different constructions. The accompanying drawing, therefore, is submitted merely as showing the preferred exemplification of the invention.

In the said drawing:—

Figure I is a front elevation or outside view of this improved ventilating device, a portion thereof being broken away to show 40 interiorly located parts;

Fig. II is an edge view of the same, looking up from the lowermost line of Fig. I, a portion being sectioned to disclose parts situated interiorly thereof;

Fig. III is a rear or inside view, showing the device as seen from the lower side of Fig. II, a portion being removed to illustrate the interior construction;

Fig. IV is an enlarged fragmentary cross-section taken from the line IV—IV of Fig. I, looking in the direction indicated by the adjoining horizontal arrows;

Fig. V is a similarly enlarged fragmentary end view of the device as it appears looking towards the right from the upper left-hand corner of Fig. I; and

Fig. VI is a fragmentary longitudinal section, on the same enlarged scale, taken from the line VI—VI of Fig. I, viewed in the direction pointed out by the vertical arrows thereto appertaining.

The reference numerals 11 and 12 designate side plates, which are located a certain distance apart one from the other, so as to leave therebetween a space A of predeter-

mined width, depending on the thickness of the door to which the ventilating device is to be applied.

Air guiding vanes 13 are produced in the outer plate 11 by cutting three-sided slits therein, such as are clearly shown in the left half of Fig. I and the right half of Fig. III. These vanes are bent obliquely inwardly of the space A as indicated in Fig. II, and thus provide elongate apertures 14, leading into the same. Intervening between the several apertures, are bridges 15, which are reinforced by hollow ribs 16, struck up from the inner face of the plate.

Similar air directing vanes 18 are also formed out of the plate 12, but the latter point right angularly inward into the space A, as Fig. II shows. However, the slitting of this plate produces like apertures 19, separated by bridges 20. These bridges of the plate 12 are smooth-surfaced throughout.

The free, inner extremities of the said vanes 13 and 18 may be offset to such extent that they are made to pass one another outwardly beyond the middle of the said space A, as seen to best advantage by reference to Figs. IV and V. According to the arrangement adopted for the embodiment of the invention herein exemplified, the apertures 14 and 19, intermediate the vanes in the two sets 13 and 18, are positioned substantially opposite the bridges 20 and 15, respectively. As shown, the oblique vanes 13 are made shorter than the apertures 14 from which they are slotted, this is when the space A is of mediocre width. Generally, the wider the plates 11 and 12 are spaced apart, the longer the vanes 13 must be in order to prevent direct rays of light passing through the said apertures 14 and 19, as also to block the sight thereacross.

Interposed between the plates 11 and 12, in associated relation with their inner faces and the transverse ends of the vanes 13 and 18, are channel-shaped members 22 and 23, which extend for the entire length of the ventilator. These members constitute spacers that hold the plates 11 and 12 at the predetermined distances apart, and their web portions bound the narrow sides of the space A left between the said plates, in all instances.

As plainly indicated in Figs. IV and V, the outer longitudinal portions 24 of the plate 11 are folded inwardly around the adjacent flanges 25 of the members 22 and 23, respectively, and the free edges 26 of these same portions are made to lie close against the webs of the said members. Thus, it will be understood, the latter are securely fastened in position.

The opposite flanges 28 of the members 22 and 23 are tied to the plate 12 by means of lugs or ears 29, shorn out of that part of the plate which sublies the latter-named flanges,

as represented in Figs. IV and V. The lugs are first bent up, then laid over and pressed down upon these flanges. In this case also, the free ends or tips of the lugs 29 are made to 5 abut against the webs of the channel-shaped members, so that not only is the plate 12 maintained in proper correlative position with their said webs, but the latter are firmly secured in juxtaposition to the vanes 13 and 10 18. The openings left in the plate 12, after forcing out the lugs 29 therefrom, are indicated at 30, the same being located under the flanges 28 of the channel-shaped members 22, 23 and substantially opposite the 15 smooth-surfaced bridges 20.

The outer longitudinal portions 32 of the plate 12 are folded in the same direction as the corresponding parts 24 of the plate 11, that is, so as to lie outwardly beyond the 20 plane of the former. The free edges 33 of the said portions 32 are spaced from the plate 12 sufficiently to constitute a pair of guides 34, the extreme outer limits of which are given each a liberal inside curvature, as 25 denoted at 35. It will be observed that the said outer portions 24 and 32 of the two plates 11 and 12 are situated in approximately the same longitudinal planes and 30 form the transverse margins of the ventilator.

In the guides 34 is fitted a slide 37, translatable lengthwise of the adjacent plate 12. The lateral edges of this slide are preferably reinforced or thickened, as by bending the 35 same inwardly over or upon themselves, in the manner indicated at 38, thereby offsetting the slide's body from the plate sufficiently to preclude the rubbing of their entire surfaces one against the other, which 40 would streak and abrade the paint thereon, as also render them liable to stick together. The frictional contact between the folds 38 and the plate 12 is limited to the width of the former and their counterparts on each 45 side of the slide 37 that rest upon the opposite inner faces of the guides 34. It will be noted that the rounded outer edges of the slide are of considerably less curvature than the corresponding inside portions of 50 the guides, so that the former obtains in the latter a liberal freedom of motion, accompanied with lessened friction and a practically noiseless operation.

The slide 37 is provided with a number of 55 openings 40, conforming with that of the apertures 19 in the plate 12, both being similar in outline and arranged to register with one another. The opening 40 are separated by bridges 41, which also are reinforced by hollow ribs 42, struck up therefrom. These ribs are of configuration corresponding to that of the ribs 16, previously mentioned, and together they give both 60 sides of the ventilator a like appearance.

At 44 is indicated a manipulating knob

for the slide 37, which may be secured in any suitable manner to one of the ribs 42, in plain view of a person facing the door, so that it can be easily reached whenever it is desired to open, close, or graduate the 70 communication between the series of apertures 14, 19 in the plates 11, 12 and the openings 40 in the said slide.

With the object both of strengthening the guides 34 and providing a stop to limit the 75 travel of the slide 37 in either direction, a retainer 46 in the form of a bar of flattened cross-section is lodged across each pair of the guide members at the ends of the plate 12. These bars 46 may be held in their as 80 signed positions by rivets or the like 47, fastening them to the plates.

It will be observed that the extremities of the said bars which enter the guides are nicked down, as at 48, and buffers 49, 85 such as blocks of rubber or other resilient material, are lodged thereagainst, as represented in Figs. III and VI. Obviously, these buffers act to cushion the impact of the slide as it comes to a stop at the end of 90 its travel in either direction within the guides, thereby eliminating any noise on that score. It is understood that when the buffers 49 are undergoing deterioration they 95 may be discarded and new ones substituted.

The improved ventilator herein described and illustrated is especially designed for insertion into the top panel or upper part of a door, as exemplified in Fig. II (by dot-and-dash lines) where B represents the side 100 stiles of a door, and C denotes moldings that serve to retain the device in proper position, besides giving the insert a finished appearance. Notwithstanding this showing, the device can nevertheless be employed for 105 any other appropriate purpose, where it is desired to establish a circulation of air across some primary support without permitting direct light rays therethrough, or allowing objects to be discerned or viewed 110 from one side thereof to the other.

It is to be noted that this improved device is wholly metallic in its character, as well as self-contained. The transverse ends of the apertures in the front and rear plates, 115 as also of the openings in the slide, are made flush with the inner faces of the channelled members, so that it is an easy matter to blow or clean out dirt from the interior of the space A enclosed by the associated 120 plates and members. There is nothing to get out of order, or endanger by tampering with the same. Such chance as the slide might have of binding or rattling is obviated by the very nature of its construction and 125 arrangement. The ventilator in its entirety may be given a coat of paint to conform to the finish on the door, without interfering in the least with its successful operation.

While a certain preferred embodiment 130

of this device has been shown and described, it will be understood that changes in the form, arrangements, proportions, sizes and details thereof may be made, without departing from the scope of the invention as defined by the appended claims.

Having described our invention what we desire to secure by Letters Patent and claim, is:—

10 1. In a ventilating device of the character described, the combination with a pair of apertured plates set apart to provide a space of predetermined width therebetween and air-guiding vanes located intermediate the 15 apertures in said plates, of flanged members the web portions of which serve to close the longitudinal sides of said space by being interposed between the plates in abutting relation to the transverse ends of 20 said vanes, and counter disposed means formed near the edges of the plates adapted to engage the opposite inner faces of the flanges and lie substantially flush with the outer sides of the webs of said members to 25 tie the said parts together.

2. In a ventilating device of the character described, the combination with interspaced plates having each a plurality of apertures and air-conducting vanes intervening there- 30 between, of flanged members closing the longitudinal sides of the space intermediate said plates, the latter extending sidewise beyond said members, the free edges of one plate forming folds engaging the adjacent 35 flanges of the members, and lugs formed near the edges of the other plate engaging the adjacent flanges oppositely formed on the members; said folds and said lugs being brought into abutting relation with the 40 outer faces of the members within their said flanges.

3. In a ventilating device of the character described, the combination with apertured plates placed in parallelism at a predetermined distance apart one from the other and air-directing vanes positioned in the spaces occurring between said plates, of channel-shaped members situated on opposite sides of the latter serving to close said 50 space, retaining means fashioned from lon-

gitudinal edge portions of the plates holding them and said members securely together, guides formed by the edges of one plate curved outwardly therefrom, and a slide operable in said guides having openings adapted to be brought into or out of register with the apertures in the plates.

4. In a ventilating device of the character described, the combination with apertured plates spaced apart one from the other and air-guiding vanes located intermediate the apertures in said plates, of flanged members interposed between the plates adjacent their longitudinal edges, one plate having the latter bent around the adjoining flanges of both members, ear-like fastening means pertaining to the other plate folded over the contiguous opposite flanges of the said members, guides formed with said other plate including lips projecting therefrom in a like direction to said bent-around edges, and a reciprocable register slide in said guides retained therein by said lips, said slide having its lengthwise extending edges doubled upon themselves in the same direction as said folded means.

5. In a ventilating device of the character described, the combination with a pair of apertured plates separated by a space of predetermined width and air-guiding vanes located in said space, of laterally disposed members conjoined with said plates on opposite sides of the same, guides formed by outwardly turned longitudinal edges of one of the plates, a slide arranged to reciprocate in said guides having openings capable of being brought into or out of register with the apertures in the plates, elements of substantially the same thickness as the depth of the guides and having notched end portions lodged in the terminals thereof, and exteriorly invisible resilient means entered in said terminals against said portions, said means serving to limit the travel of said slide, the latter being held beyond said apertures and said openings so as to avoid interfering with the circulation of air therethrough.

ARTHUR WADE.
HARRY L. VAN ZILE.
